SUPPORT FOR HEAT TREATING CONTAINERS

Filed Feb. 27, 1943

UNITED STATES PATENT OFFICE

2,384,617

SUPPORT FOR HEAT-TREATING CONTAINERS

Henry H. Harris, Champaign, Ill.

Application February 27, 1943, Serial No. 477,475

2 Claims. (Cl. 263—47)

My invention relates generally to work containing receptacles, and in particular to work containing receptacles adapted to be moved through a heat treating furnace. My invention will be described in respect to a work support used in the carburizing process, but its use need not necessarily be so limited, the device being equally usable in other processes.

When conventional containers are used in heat treating furnaces, the work to be treated is placed inside the boxes and embedded in a carbonaceous material such as bone dust and the like. The boxes are then covered over with heavy trays, and inverted, with the trays on the underside, and in this position placed on skid rails or tracks within the furnace. The trays are arranged within the furnace in end-to-end or side-by-side abutting relationship and thrust applied to the rearmost tray is transmitted down to the line from tray to tray to the endmost tray. In this manner, the loaded trays are passed through the cycle in step-by-step movement until pushed out at the discharge end of the furnace.

The trays support the work being treated as well as the weight of the carbonaceous material; the trays serve as closures for the boxes and support the boxes within which the work is contained, and they also serve to transmit the moving thrust from one tray to the next, down the line. In use, the trays are subjected to the rough handling incident to the process, as well as to extremely high furnace temperatures and sudden changes in temperatures, and all too often the trays develop cracks, shrinks and warpage and have to be replaced at relatively frequent intervals. Conventionally, both the trays and boxes have been made of thick section material, at some expense and with appreciable weight, and their too frequent failure in use involves considerable cost. The weight of the boxes and trays is also a factor in the power needed to move them through the furnace.

The general objective of this invention is the simplification of the apparatus used in supporting the work being treated, while retaining all the functions of the devices conventionally in use.

The main object of my invention is the provision of a work container, means to close same and means to support same during movement through a furnace. In my device, I have done away with the heavy tray-closure used as a support, and close the container with one element and support the container on other elements.

Another object of my invention is the provision

of a work container and support means therefor keyed thereunto for movement through a furnace.

Still another object of my invention is the provision of a work container and support means therefor keyed thereunto, the supports receiving and transmitting the thrust of travelling movement through the furnace.

Further objects of my invention will appear during the course of the following description of several illustrative embodiments thereof.

In the drawing annexed hereto, and forming a part hereof,

Figure 1 is a plan view, partly in section and partly broken away, of one form of device constructed according to and embodying my invention;

Fig. 2 is a longitudinal section along the line 2—2 of Fig. 1 also partly broken away; and

Fig. 3 is a transverse section on the line 3—3 of Fig. 1.

My device, indicated generally by reference numeral 10, comprises a pair of track or rail overlying shoes or skids 12, 14, of substantially equal length. Shoes 12, 14 are cast or otherwise formed of high heat and corrosion resisting alloy material, and each comprises a flat-bottomed skid plate 16 and a pair of integrally formed vertically upstanding side walls 18, 20. The outer wall 18 on each shoe extends upwardly and inwardly over plate 16, short of the center thereof, and the inner wall 20 of each shoe also extends upwardly and inwardly over the plate, short of the center thereof. The spacing between the wall-ends defines a channel 22 extending substantially the full length of each shoe. As seen in Fig. 3, the inner walls 20 are shorter than the outer walls 18. A number of laterally spaced apart blocks 24, 24 are formed on top of walls 20 along the edges of channels 22, the purpose of which will be given below.

One of the shoes, as 12, may have a pair of integrally formed legs 26, 26 depending from the sides thereof, defining a channel 28. Legs 26, at each end of the shoe are flared outwardly, as at 30, to serve to guide the shoes onto the skid rails or tracks, legs 26, 26 straddling one of the tracks or rails within the furnace to keep the shoes aligned thereon.

I provide a plate 40, which may be of generally rectangular shape, but with rounded corners. Plate 40 need not be particularly thick, but may be slightly bowed and provided with a few strengthening transverse corrugations 42. Plate 40 need be strong enough to support only the weight of the charge being heat treated and the

weight of the carbonaceous material. At each end thereof, in the center, plate 40 has integrally formed thereon a leg 44, extending downwardly and outwardly therefrom as at 46, and terminating in a ring 48. A loop handle or bail, as 50, may be pivotally secured within ring 48.

On the floor of channels 22, 22, a short, vertically upstanding rib, as 21, may be formed integral with the shoe, extending the full length of the channels 22.

My box or container 60 is cast or otherwise formed of high heat and corrosion-resisting alloy material, and is of generally conventional rectangular shape, the sides of which are no thicker than the width of channel 22. Box 60 is preferably formed of greater length and width than plate 40, and preferably of such width as to overlie a pair of rails or tracks within the furnace. A catch 62 is formed on the outside of each of the end walls of the box.

In use, box 60 is inverted, open end upwards, and charged with the work to be treated and with the carbonaceous material. The plate 40 is then fitted within the open end of the box and loops or bails 50 swung down and over catches 62. Shoes 12, 14 may then be inverted and fitted over and onto the sides of box 60, or the box may be inverted and set into the shoes. Whichever sequence of steps is followed, the entire combination is then disposed atop a pair of parallel tracks or rails within the furnace.

As seen in Fig. 1, the ends of shoes 12 and 14 extend beyond walls 18, 20. Inner wall 20 is shorter than outer wall 18, and at the ends thereof, the walls curve inwardly of the shoe to a point where the upstanding portion of the wall merges into the floor portion of the shoe, as at 10. The outer walls 18 curve correspondingly, keeping the width of channel 22 constant. The curvature of the channel serves, therefore, to locate shoes 12, 14 on box 60, and insure proper alignment of the shoes. A vertically upstanding, apertured lug or ear member 72 is formed at each end of the shoes, preferably integral with the shoes, and I may provide my box 60 with a pair of horizontally extending arms 74, 74 at each end thereof, to line up with the lugs 72. A pin passed through registering apertures in the arms and lugs will serve to further lock the box onto the shoes.

After the loaded box is inverted, spot welds may be formed as at 64, 66, to further lock plate 40 to box 60. The weight of the charge will cause plate or web 40 to bear down on shoes 12, 14 and the alignment of bails 50, 50 on catches 62 will center the plate against blocks 24, 24.

A number of loaded containers, mounted on shoes such as those hereinabove may then be disposed within the furnace in end-to-end relationship, the shoes of one butting against the

shoes of the adjacent unit. Thrust applied to the shoes of the endmost unit will be transmitted down the line to move same either continuously or intermittently, through the furnace.

5 The closures, plates or webs 40 take no thrust. The boxes 60 similarly do not receive or transmit any thrust, and they may be formed of much lighter and thinner section material than heretofore.

10 The device of my invention, as a unit, is easily assembled for use, and just as easily dismantled. Plates, boxes, shoes, etc., may be formed of uniform size, so as to be interchangeable with parts of other units. The shoes may be formed of extra heavy material, since they must absorb and transmit the moving thrust.

The box is, in and of itself, a rigid beam member, capable of maintaining its shape if supported at any two or more points. A heavy tray, 20 as in conventional practice, is not at all necessary to support the box, and in my invention, the thrust tubes or shoes 12 and 14 support the box, the plate and the work thereon. The thrust tubes and box may be formed of uniform section, 25 and the use of these thrust tubes localizing all compression strains results in much longer alloy life. A weight saving of up to 45% is secured with my device, which is operationally more efficient than the conventional arrangements.

30 Having now described my invention, what I claim and desire to secure by Letters Patent is:

1. In combination, for use in a heat treating furnace having rails therewithin, an inverted open-mouthed work container, a closure therefor fitting into the container, cooperating means on the closure and on the container to maintain the closure within the container, and a plurality of container- and closure-supporting rail-overlying means, said rail-overlying means being longitudinally channeled to receive the container therewithin and support same thereon, said rail-overlying means also having a platform portion thereon to support the closure.

2. In combination, for use in a heat treating 45 furnace having rails therewithin, an inverted open-mouthed work container, a closure therefor fitting into the container, cooperating means on the closure and on the container to maintain the closure within the container, and rail-overlying

50 means comprising a plurality of elongated thrust beams to support the container and the closure, each beam having a pair of walls extending upwardly thereof to define a longitudinally extending channel therebetween to receive the container therewithin and support same thereon, one of the walls of each thrust beam being bent over inwardly thereof to form a platform portion to support the closure thereon.
